GOTTLIEB KELLER, OF BRUGG, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND.

ELECTRICALLY-HEATED KILN.

Application filed December 13, 1926, Serial No 154,448, and in Germany January 6, 1928.

This invention relates to kilns of a type suitable for such uses as the burning of limestone or the like for production of quicklime.

5 One of the objects of the invention is the provision of a kiln wherein the burning temperatures may be accurately controlled so that the procedure may be carried on at the most efficient temperature and overburning avoided.

10 Another object is the provision of a construction which will contribute to uniformity in the heating of the material subjected to the process, for the purpose of preventing 15 the occurrence of unburned or insufficiently burned material in the product.

Another object is the provision of a construction adapted for continuous operation by virtue of the fact that the material is 20 passed through the kiln, new raw material being supplied as burned material is withdrawn, without requiring any cessation of the burning.

25 Another object is the provision of a construction which will facilitate and promote the feeding of the charge through the kiln.

Other and further objects will be pointed out or indicated hereinafter or will appear to one skilled in the art upon an understanding 30 of the invention or its employment in practice.

In the accompanying drawing forming a part of this specification, I illustrate one structural embodiment of the invention, but 35 the same is presented for illustration only and is not to be accorded any interpretation having the effect of limiting the claims short of the true and most comprehensive scope of the invention in the art.

40 In the drawing,

Fig. 1 is a diagrammatic illustration in the nature of a part sectional elevation of a kiln suitable for lime burning and containing features of my invention;

45 Fig. 2 is a diagrammatic illustration in the nature of a cross section of same on substantially line 2—2 of Fig. 1; and

Fig. 3 is a detail in the nature of a transverse sectional view of one of the heaters.

50 In the treatment of various materials, such as the burning of limestone or other natural forms of calcium carbonate for the production of quicklime, a uniform heating of the pieces of the raw material is of utmost im-

portance, if a good and uniform quality of 55 product is to be obtained. For a pure product, it is important to avoid the smoking of the material, as from the smoke of the heating fuel. Likewise, the temperature should be kept as low as possible, consistent with 60 the carrying on of the necessary combustion, as high temperatures cause impurities in the limestone to interact with the quicklime formed, producing fusible silicates, which fill the pores and interfere with the subsequent slaking with water or other contemplated treatments of the lime. Local underheating will result in unconverted limestone in the product.

The present invention makes provision for 70 the necessary heating of the raw material by electrical means to a temperature whereat the combustion proceeds at a sufficiently rapid rate, the burned product being withdrawn at the bottom of the kiln and the 75 raw material supplied at the top, the burning taking place as the material passes through the kiln, so that the operation of the installation may be carried on continuously. The heating elements are disposed in 80 the path of the material in a distributed arrangement, so that the material passes into intimate association with them and uniform heating of the material is accomplished.

The nature of the invention will be as- 85 certained in more detail from the illustrative arrangement shown in the drawing, which is of diagrammatic nature, and illustrates the organization of a construction suitable for the burning of limestone or the 90 like into quicklime. The kiln is in the nature of a hollow tower having the refractory walls 10 affording the interior burning chamber 11 into which the material is charged at the top. The charge is sup- 95 ported on a grate 12 affording passage there- through for the burned material, which drops into the pit 14 and may be withdrawn through the wall opening 15. A number of heating elements 16 are supported on the 100 walls in spaced relationship and extend across the chamber 11. These heating elements are in the nature of hollow bars of a strong heat resisting and non-oxidizing metal, and contain the electrical resistance 105 elements 17 having electrical insulating coverings 18. Suitable electrical connections are arranged at the end of the heating ele-

ments for supplying the resistance elements with electric current. In order to afford maximum heating surface and strength, the heating elements may be given a wedge or ovaloid sectional form, as illustrated in Fig. 3, the narrower side being directed upwardly. Preferably, their mounting on the walls is such that they may be rocked, after the fashion of grate bars, to loosen the charge material and promote its free descent. The arrangement of the heating members is such as to accommodate passage of the charge between and around them and to give uniform heat distribution across the entire area 15 of the chamber 11. They may be placed at different levels and extend in crossing directions, as illustrated.

In operation, the resistance elements are supplied with the necessary electric current 20 to develop the desired degree of heat, which is imparted to the fragmentary material in the chamber 11 through the walls of the heating members 16. Air is supplied to the chamber 11 through the grate and, if desired, through the walls above the grate, 25 in quantities requisite for the combustion of the material, and the carbon dioxide and unreduced gases pass out of the chamber at the top. As the fragmentary material burns, 30 it becomes friable and breaks up and is passed through the grate into the pit 14, so that the charge gradually feeds downwardly through the chamber 11 and through the heated zone or zones produced by the 35 heating members. Due to the distributed arrangement of the heating members, the material of the charge, incident to its progressive feed by gravity, is given a uniform heating to the desired reaction temperature, 40 with the result that a uniform product re-

sults. Inasmuch as the temperature of the heating members may be definitely controlled, overburning and fusion of the treated material may be definitely avoided. Since the heat is derived from a smokeless 45 source, contamination of the product from fuel smoke or ash is avoided.

What I claim is:

1. In apparatus of the character described, means providing a vertically-disposed heating chamber, heat-radiating elements disposed within said chamber and supported in spaced relation with respect to each other in such manner as to provide for retarded gravity-induced movement of 50 material in said chamber, and heating means disposed within said elements and sealed thereby against direct contact with said material.

2. In apparatus of the character described, 60 means providing a vertically-disposed heating chamber, elongated hollow substantially horizontally disposed heat-radiating elements having an upwardly tapered transverse section and supported within said chamber in spaced relation with respect to each other in such manner as to provide for retarded gravity-induced movement of 65 material in said chamber, the lower enlarged edges of said elements providing with the 70 walls of said chamber a pivotal support for said elements permitting of rocking movement of the same, and heating means disposed within said elements and sealed thereby against direct contact with said 75 material.

In testimony whereof I have hereunto subscribed my name at Zurich, Switzerland, this 26 day of November A. D. 1926.

GOTTLIEB KELLER.
